Fritz Andreae,
G. Muller, Attorney
LLP.

UNITED STATES PATENT OFFICE

FRITZ ANDREAE, OF COLOGNE, GERMANY

WARP PILE FABRIC

Application filed June 26, 1931, Serial No. 547,111, and in Germany March 28, 1931.

The invention relates to a new type of fabric having an uncut pile face consisting of highly twisted continuous filament crepe threads which is particularly suitable for 5 fine silk and artificial silk materials, and possesses substantial advantages over the known types of fabrics.

In the accompanying drawing—

Fig. 1 is an end elevation of the backing 10 with loops before they become automatically spiraled, and

Fig. 2 is a sectional view of the fabric with the loops spiraled.

The known fabrics have in particular the 15 defect that they cannot stand pressure, the pile bending aside at the points where pressure is applied, and not recovering its erect position spontaneously. The fabric consequently assumes an unpleasant appearance, 20 which can only be removed, to a certain extent, by steaming or the like.

It has already been proposed to make the 25 cut pile of a fabric from tightly twisted threads, in order to impart a curly effect to the tufts resulting from the cutting of the pile. Such a fabric, however, also exhibits merely a relatively low compression strength, 30 particularly because the individual tufts soon become completely untwisted during wear, there being nothing to prevent that occurrence.

According to the invention, the aforesaid 35 defects are remedied. The invention relates to a pile fabric, with uncut twists formed of spiraled loops such as strongly overtwisted filling threads such as crepe threads which when looped upon the weft and warp threads or the base, and as the loops are unrestrained 40 they will take the form of upstanding and spiraled or intertwined looped and uncut tufts, the spiral form of the tufts being self produced and maintained, so that in use the tufts will embody automatic intertwined and upstanding tufts, in contradistinction to the 45 pile chenille and uncut velvets. As shown in Fig. 2, the individual, uncut loops *a*, thus acquire a cork-screw twist. The advantage of this new type of crepe pile fabric consists primarily in a quite extraordinary increase in 50 compression strength and resistance of the

pile. For example, the new fabric can be rumpled and twisted to any extent, without producing the slightest creasing of the material, which, on being spread out again, is 55 exactly as smooth as before. Moreover, the pile of this new fabric stands perfectly erect. Consequently, the new fabric can be juxtaposed in any convenient manner, when being worked up into clothing and the like, 60 without any necessity for considering—as 65 was previously the case—the life of the pile.

In manufacturing the new fabric, it is advisable to use a strongly overtwisted thread (crepe thread) for making the pile. When 70 the finished fabric is afterwards dyed in the piece, the individual loops *a* will then automatically twist in spiral or corkscrew form, as shown in Fig. 2. Other methods, however, might also be adopted for producing the 75 new fabric.

The character of crepe thread is well known and, as stated above, the fabric when dyed in the piece will cause the loops to possess certain characteristics. Obviously, this 80 same result will occur when the fabric is 75 moistened as it is when being treated or subjected to the finishing processes.

Furthermore, it may be stated that the crepe threads to which reference has been 85 made may be defined as consisting of fibres of continuous length.

I claim:

1. The method of producing a fabric which consists in simultaneously interweaving with a backing of warp and weft threads, an uncut pile face consisting of highly twisted continuous filament crepe threads passed under and over the weft threads and looped selectively and successively between two weft threads of the backing, inserting a loop supporting element while said crepe threads are being secured in place, and then withdrawing the said loop supporting element, whereupon the said crepe threads twist to form a plurality of loops projecting substantially at 90 right angles to the warp and weft of the fabric.

2. A fabric having a crepe-like pile facing, the pile of which is uncut, said pile consisting of loops of highly twisted continuous 100

filament crepe yarn interwoven between the warp and weft threads thereof, standing approximately at right angles to the warp and weft and being twisted to produce a plurality of resilient spirals.

In testimony whereof, I affix my signature.

FRITZ ANDREAE.
